[57] CLAIM

The ornamental design for a vehicle rail module exterior surface incorporating a handle, coathook and lamp, as shown and described.

DESCRIPTION

FIG. 1 is a front view of a vehicle rail module exterior surface incorporating a handle, coathook and lamp constructed in accordance with the present invention;

FIG. 2 is a cross-sectional view taken through the line 2—2 of FIG. 1, illustrating the handle in a first operative position; FIG. 3 is a view similar to FIG. 2, showing the handle in a second operative position;

FIG. 4 is a cross-sectional view taken through the line 4—4 of FIG. 1, with the handle in its first operative position; FIG. 5 is a view similar to FIG. 4, showing the handle in its second operative position;

FIG. 6 is a cross-sectional view taken through the line 6—6 of FIG. 1, showing the coat hook in a first operative position; and, FIG. 7 is a view similar to FIG. 6, showing the coat hook in a second operative position.

It being understood that the back of the vehicle rail modules of the first and second embodiments is plain and unornamented and further not visible in ordinary use.
